UNITED STATES PATENT OFFICE.

FRANK F. SHILLING, OF TIRO, OHIO, ASSIGNOR OF ONE-HALF TO ADOLPH LEIMANN, OF MOOREFIELD, OHIO.

DESIGN FOR A CORN-PULPER.

SPECIFICATION forming part of Design No. 28,101, dated December 28, 1897.

Application filed November 11, 1897. Serial No. 658,213. Term of patent 14 years.

To all whom it may concern:

Be it known that I, FRANK F. SHILLING, a citizen of the United States, residing at Tiro, in the county of Crawford and State of Ohio, 5 have invented and produced a new and original Design for a Corn-Pulper; and I do hereby declare the following to be a full, clear, and exact description of the same, reference being had to the accompanying drawings, forming a part thereof.

My invention has relation to a novel design for a corn-pulper for kitchen use, and is illustrated in the accompanying drawings, in which—

15 Figure 1 is a perspective view of a corn-pulper embodying my invention; Fig. 2 a longitudinal sectional view, Fig. 3 a cross-sectional view, and Fig. 4 an end view, of same.

20 My invention consists of the unitary design illustrated in the accompanying draw-

ings, and comprises a block or plate 1, having a plane bottom 2 and parallel plane sides, said block being formed with a transverse vertical slot 3, having a vertical intersecting 25 groove 10 in each of its side walls, as shown. The upper side or face 4 of the said block is also formed with a central longitudinal groove 5, bounded at opposite sides by parallel ribs 6, and in this groove is a transversely-disposed segment-shaped plate 7, formed with a series of V-shaped teeth 8.

Having thus described my invention, I claim—

The design for a corn-pulper, substantially 35 as herein shown and described.

In testimony whereof I affix my signature in presence of two witnesses.

FRANK F. SHILLING.

Witnesses:

JOHN B. STOCKDALE,
ELIZABETH STOCKDALE.
